UNITED STATES PATENT OFFICE

154,767

DESIGN FOR A LIGHT BULB SHADE

Marvin Glass, Chicago, Ill.

Application February 12, 1948, Serial No. 144,433

Term of patent 7 years

(Cl. D48—16)

To all whom it may concern:

Be it known that I, Marvin Glass, a citizen of the United States, residing at Chicago, county of Cook, and State of Illinois, have invented a new, original, and ornamental Design for a Light Bulb Shade, of which the following is a specification, reference being had to the accompanying drawing, forming a part thereof.

Fig. 1 is a front view of a light bulb shade, showing my new design.

Fig. 2 is a top plan view thereof.

Fig. 3 is a rear perspective view, and

Fig. 4 is a side view.

The dominant features of my design reside in those portions shown in full lines.

I claim:

The ornamental design for a light bulb shade, as shown and described.

MARVIN GLASS.
